GODFRIED J. MAYER, OF BUFFALO, NEW YORK.

CARBURETER.

1,089,423.

Specification of Letters Patent. Patented Mar. 10, 1914.

Application filed January 5, 1911. Serial No. 600,867.

To all whom it may concern:

Be it known that I, GODFRIED J. MAYER, a citizen of the United States, residing at Buffalo, in the county of Erie and State of New York, have invented new and useful Improvements in Carbureters, of which the following is a specification.

This invention relates to improvements in carbureters for internal combustion engines, and it has for its objects the provision of simple and effective means for automatically regulating the admission of auxiliary air to the mixing-chamber when the speed of the engine increases so as to prevent rarifying the mixture due to the admission of a greater volume of auxiliary air than would be proportionate to the gasolene or other explosive fluid drawn into the engine; to so govern the admission of air into the carbureter that when starting the engine, the flow of gasolene from the aspirating nozzle will be increased; and to so govern the supply of air, that when running the engine at low speed with a load and the throttle of the carbureter is opened, the in-rush of air through the auxiliary air-inlet is controlled so that under all conditions the proper supply of air and gasolene is obtained.

Another object is to so construct a carbureter that the tension of the auxiliary air valve can be easily regulated; and to otherwise improve on carbureters now in use.

The invention consists in the construction, arrangement and combination of parts to be hereinafter described and particularly pointed out in the subjoined claims.

In the accompanying drawings.—Figure 1 is a central vertical section of the carbureter. Fig. 2 is a perspective view of the auxiliary air-inlet valve and the piston of the dash-pot connected therewith. Fig. 3 is a detached perspective view of the dash-pot chamber. Fig. 4 is a side elevation of the valve in the main air-inlet tube.

Referring now to the drawings in detail, like numerals of reference refer to like parts in the several figures.

The reference numeral 4 designates a hollow casting providing a mixing-chamber 5 having a lateral extension 6, a carbureting-chamber 7 depending from said mixing-chamber, and a mixture-outlet 8 extending upward from said mixing-chamber and surrounded by a hot-air or hot-water chamber

9 provided to heat the mixture as it passes therethrough. In the mixture-outlet is a throttle-valve 10, such as commonly used in carbureters of this type. The depending carbureting-chamber 7 has a reduced extremity 11 into which is threaded a needle-valve 12 to regulate the flow of gasolene or other explosive fluid into the aspirating-nozzle 13 extending centrally into the carbureting chamber. Said last-mentioned chamber extends centrally through a gasolene feed-chamber 14, the bottom of which has a threaded opening 15 to receive a correspondingly threaded portion 16 of said carbureting-chamber; said threaded portion 16 projecting through the bottom of the gasolene feed chamber 14 and having a nut 17 applied thereto which impinges against the underside of the bottom of said gasolene feed chamber with packing material 18 between the two.

Threaded onto the threaded portion 16 of said carbureting-chamber, is an L-shaped air inlet-tube 19 through which the primary air is drawn and from which it passes up through the carbureting-chamber 7 so as to have an aspirating effect on the nozzle 13. Located in said air-inlet tube, which furnishes the main supply of air to the carbureter, is a butterfly valve 19^a having one wing thereof cut away, as at 19^b, to provide a small opening for the admission of air when said valve is in closed position. The gasolene is fed to the aspirating-nozzle through a passage 20 and the gasolene is retained within the gasolene feed chamber 14 at the desired level by a float 21 serving to open and close a valve (not shown) controlling the admission of gasolene to the gasolene feed-chamber, as is common.

The lateral extension has an auxiliary air-inlet tube 22, herein shown as separate from the casting 4, but not necessarily so; said tube being secured to the casting 4 in any suitable manner such as by lugs 23 through which are passed screw bolts 24 that take into the casting 4. Said auxiliary air-inlet tube has one end extending into the extension 6 of the mixing-chamber, and it is also provided with a valve 25 whereby the volume of air admitted through it may be regulated, and whereby when said valve 25 is closed, the vacuum in the carbureting chamber is increased to increase the flow of gasolene when starting the engine.

The throttle valve 10 has its stem extending through the carbureting chamber so that it may be actuated in any approved manner, and the valves 19^a and 25 also have their stems extending through the walls of their respective containing tubes. To the valve 19^a, a lever 42 is secured which has connection with one arm of a bell crank lever 43 through the medium of a rod 44, the other 5 arm of said bell crank lever having an operating rod 45 secured thereto so that the two valves move in unison, these valves being so positioned relative to each other that they open and close together.

15 While I have shown the auxiliary air-inlet tube secured to the extension of the mixing-chamber, such a tube is not absolutely necessary to the successful operation of my invention, and in a broad sense, said tube simply 20 serves as the auxiliary air-inlet. In alinement with said auxiliary air-inlet or inlet tube, is a threaded opening 26 and in the exact disposition of parts herein shown, said opening is formed in the bottom wall 25 of the extension 6 of the mixing-chamber. Connected to the mixing-chamber is a dash-pot 27 which in preferred form comprises a cylindrical dash-pot chamber 28 having a removable bottom 29 which is secured there- 30 to in a water-tight manner and an externally threaded sleeve 30 rising from its top and which is threaded into the opening 26 formed in the extension of the mixing-chamber; the upper extremity of said sleeve being 35 preferably tapered, as at 31. The sleeve 30 is of sufficient length to permit of adjustment of the dash-pot toward and from the auxiliary air-inlet, and in order to hold the dash-pot in any adjusted position, a jamb- 40 nut 32 is provided which is threaded onto said sleeve and impinges against the bottom of the extension 6 of said mixing-chamber. Connecting the dash-pot with the gasoline feed chamber 14 is a gasoline tube 33, one 45 end being passed through a stuffing-box 34 on the gasoline feed-chamber, and the other through a stuffing box 35 in the removable bottom of the dash-pot, a gland 36 of said last-mentioned stuffing-box serving to secure 50 said tube to said dash-pot in a water-tight manner, permitting the dash-pot to rotate around the said tube when adjusting the same relative to said auxiliary air-inlet.

Closing the auxiliary air-inlet, or more 55 particularly in the representation of my invention shown in the drawings, the inner end of the auxiliary air-inlet tube, is an auxiliary air valve 37; it having an axial stem 38 threaded into one end of a tube 39 60 which is slidable in the sleeve 30 of the dash-pot, and in the dash-pot chamber is a piston 40 having an axial rod or stem 41 which is threaded into the opposite end of the tube 39, thus holding the auxiliary air-inlet valve

and said piston in fixed relation. Surround- 65 ing the tube 39 is a coil spring 42 which bears with one end against the tapered end of the sleeve 30 and with its other end against the auxiliary air-inlet valve.

Having thus described the various parts 70 of my invention, I will now proceed to describe the relation of the same and the manner in which the parts may be adjusted and manipulated; also their operation.

The dash-pot as clearly shown is located 75 to one side of the gasoline feed chamber and consequently by reason of the connection of tube 33, the gasoline enters the dash-pot from the gasoline feed chamber and is main- 80 tained at the same level as the gasoline in said feed-chamber. Now upon starting the engine with which the carburetor is connected, the suction created by the engine produces a vacuum in the casting 4 and the air rushes into the air-inlet tube 19, then 85 passes up into the carbureting-chamber where it has an aspirating effect on the nozzle 18 and consequently carries with it the proper proportion of gasoline, which in its upward passage with the air through the 90 mixing-chamber 5, is thoroughly mixed with the air and passes through the mixture tube 8 to the engine. The tension of the spring 42 and the resistance of the gasoline in the dash-pot prevents the opening of the 95 auxiliary air inlet tube until the suction created by the engine is increased, which, however, occurs only as the speed of the engine increases, whereupon a greater quantity of gasoline is drawn out of the aspirat- 100 ing-nozzle; consequently an additional quantity of air should be admitted into the mixing-chamber to retain the proper proportional quantities of air and gasoline at all times as it passes through the outlet tube 8. 105 Therefore, as the suction increases, the auxiliary air valve 37 is caused to open and admit a quantity of air into the mixing-chamber through the auxiliary air-inlet tube 22. The amount of auxiliary air admitted 110 is controlled by the said auxiliary air-valve, consequently the additional gasoline drawn from the aspirating nozzle is only in proportion to the additional quantity of air admitted. This being regulated to a nicety 115 by the dash-pot 27 which on being raised or lowered will increase or diminish the pressure of the spring against the auxiliary air valve and as a quick opening of the air valve is checked by the dash-pot, due to the fact 120 that the piston therein must displace the gasoline contained in the dash-pot by forcing it through the small tube 33 and into the gasoline feed-chamber, the opening movement of the valve is retarded, thus prevent- 125 ing the sudden collapse of the spring 38 which would otherwise likely occur by a sudden increase of the speed of the engine.

The area of the dash-pot is comparatively small and the forcing of the gasoline from the same into the gasoline feed chamber would not affect the level of the gasoline in said feed-chamber owing to the fact that the gasoline fed from the dash-pot would be consumed by the engine about as quickly as introduced into the gasoline feed-chamber.

The connection of the valves 19^a and 25 in 10 the manner described is particularly desirable when starting a car in cold weather, since at such times it is necessary to supply a very rich mixture, and this is obtained by manipulating the operating rod 45 so that 15 both valves are moved into closed position. By this means air is admitted into the carbureter only through the small openings provided in the main air-inlet tube 19 by the cutting away of a portion of one wing of the 20 valve 19^a. Under such conditions, suction created in the carbureter by the engine, will not act upon the auxiliary air inlet valve 37, consequently there is no admission of auxiliary air and a greater quantity of gasoline is 25 delivered with each stroke of the engine. After the engine has started, the operator opens the valves 19^a and 25 to the extent desired so that the mixture gradually becomes 30 normal; and when the valve 25 is opened, the auxiliary valve 37 is free to perform its proper functions to admit the auxiliary air in proper quantities so as to provide the proper proportional delivery of gas and air to the engine.

35 By the use of my invention, the proper proportion of gasoline and air is maintained at all times irrespective of the speed of the engine; and by it, I eliminate all unsteadiness in the running of the engine, such as 40 would occur if the auxiliary valve were opened quickly and a greater quantity of auxiliary air admitted, resulting in a bad mixture and improper action of the engine.

Having thus described my invention, what 45 I claim is,—

1. In a carbureter, the combination with a gasoline feed chamber, of a casing having an air-inlet, a mixture-outlet, and an auxiliary air-inlet, means for carbureting air 50 passing through said casing, a valve for opening and closing said auxiliary air-inlet, a dash-pot chamber coaxial with said valve and adjustable toward and from the same, a piston within said dash-pot chamber rigidly 55 connected with said valve, a tube connecting said dash-pot chamber with said gasoline chamber, said dash-pot chamber being movable on said tube, and a spring interposed between said dash-pot chamber and said 60 valve.

2. In a carbureter, the combination with a casing having an air-inlet, a mixture-outlet, and an auxiliary air-inlet and having also means for carbureting air passing there-

through, of a valve for opening and closing 65 said auxiliary air-inlet, a dash-pot comprising a chamber containing a liquid and having a sleeve in axial alignment with said valve, a piston within said dash-pot chamber acting against the liquid therein, a tube 70 slideable in said casing and connecting said valve and piston together, and a coil spring between the end of said sleeve and said valve.

3. A carbureter comprising a casing having an air inlet, a mixture-outlet, an auxiliary air-inlet, and a threaded opening opposite said auxiliary air inlet and having also means for carbureting air passing there-through, a valve for opening and closing 75 said auxiliary air-inlet, a dash-pot comprising a chamber having an externally threaded sleeve threaded into the threaded opening of said casing and containing a liquid, a piston within said chamber acting against said liquid, a tube slideable in said sleeve and connecting 80 said valve and piston, and a coil spring surrounding said tube and bearing at opposite ends against said valve and the end of said sleeve entered in said casing.

4. In a carbureter, the combination with a 85 gasoline feed-chamber adapted to contain a quantity of gasoline, of a casing having an air-inlet, a mixture-outlet, an auxiliary air-inlet and a threaded opening opposite said auxiliary air-inlet and having also means 90 therein for carbureting air passing there-through, said means being in connection with said gasoline feed-chamber, a valve for 95 opening and closing said auxiliary air-inlet, a dash-pot comprising a chamber having an externally threaded sleeve threaded into the 100 threaded opening of said casing and containing a quantity of gasoline, a tube connecting said chamber with said gasoline feed-chamber so that the gasoline in said dash-pot 105 chamber is on a level with that in the feed-chamber, a piston within said dash-pot chamber acting against the gasoline therein and having connection with said valve, and a spring tending to hold said valve in closed 110 position.

5. In a carbureter, the combination with a 115 gasoline feed-chamber, of a casing having an air-inlet, a mixture-outlet, an auxiliary air-inlet and a threaded opening opposite said auxiliary air-inlet, means within said 120 casing having connection with said gasoline chamber for carbureting air passing through said casing, a valve for opening and closing said auxiliary air-inlet, a dash-pot comprising a chamber having an externally threaded sleeve threaded into the threaded opening of said casing so as to be adjustable toward and from said auxiliary air-inlet, a piston within 125 said dash-pot chamber, a tube connecting said dash-pot chamber with the gasoline feed-chamber to supply said dash-pot chamber with gasoline, said tube having connec-

tion with said dash-pot chamber to permit the latter to be rotated for adjusting the same relative to said auxiliary air-inlet and said piston having connection with said valve, and a spring acting to hold said valve in closed position.

In testimony whereof, I have affixed my

signature in the presence of two subscribing witnesses.

GODFRIED J. MAYER.
